PROTECTING DEVICE

Richard A. Packert, West Orange, and William H. Marks, Clifton, N. J.

Application October 24, 1935, Serial No. 46,470

1 Claim. (Cl. 189—56)

The invention relates to protecting devices of the type exemplified by awnings, canopies and the like, and has for its object to provide a device of the indicated type comprising a plurality of metallic sections or slats pivotally connected with each other in a novel manner to provide a construction capable of being conveniently rolled and unrolled and adapted in its operative or extended position to provide maximum protection against the elements. The invention further contemplates an arrangement in which the novel pivotal connections between adjacent sections or slats contribute to the support of the device in its operative or extended position without interfering with the rolling up of said device to its inoperative position. Other more specific objects will appear from the description hereinafter and the features of novelty will be pointed out in the claim.

In the accompanying drawing, which illustrates several forms of the invention without defining its limits, Fig. 1 is an enlarged detail view illustrating two interconnected slats in the operative or extended position of the device; Fig. 2 is a similar view illustrating the ability of said slats to develop relative pivotal movements sufficient to enable the device to be rolled up to an inoperative position; Fig. 3 is a fragmentary inside face view of the device; Fig. 4 is a detail section illustrating means for imparting a finish to the device, and Fig. 5 is a detail view of a finish imparting means or stud.

In all of its forms the protecting device comprises a plurality of slats 10 constructed of a suitable metal and arranged in adjacent parallel relation to each other, said slats 10 being of predetermined length and of such numbers as to provide a device of the dimensions and type desired. The slats 10 are provided at opposite edges with means whereby said slats 10 are pivotally connected with each other, said means including stops co-operating with each other to prevent relative pivotal movement of the slats 10 in one direction materially beyond the surface plane of the extended device and to permit relative pivotal movement of said slats 10 in the opposite direction sufficient to enable the device to be rolled up to an inoperative position. The features referred to above will be more specifically described hereinafter.

When the device is intended to function as an awning, the one end of the device is secured in any conventional manner to a customary rotatable roller mounted in any well known way, for instance at the upper portion of a window or other

opening. The opposite end portion of the device may be suitably connected in any conventional manner with the customary extending frame pivotally connected, for instance at the lower portion of the aforesaid window or other opening.

When constructed to function as a canopy the device may be supported in its extended position upon a conventional canopy frame and in such case may consist of two sections adapted to be 10 adjusted to an extended operative position either lengthwise of the canopy frame, or transversely thereof as will be apparent. In either case rotatable rollers similar to the previously mentioned roller may be rotatably supported in operative 15 relation to the canopy frame for the purpose of enabling the device to be rolled up to an inoperative position at will.

While the device is particularly designed to function either as an awning or as a canopy, it 20 will be obvious that the novel features may be embodied in other types of protecting devices.

As shown in Figs. 1 and 2 the metallic slats 10 are preferably curved to a slight extent in cross-section although it will be understood that 25 this is not absolutely essential. The means located at the opposite edges of the slats 10 whereby the latter are pivotally connected with each other comprise coiled portions 19 and 20, the coiled portion 19 of one slat being interconnected with the 30 coiled portion 20 of the next adjacent slat 10, as shown in Figs. 1 and 2. The means whereby the pivotal movements of the slats 10 relatively to each other are controlled comprise stops included in the coiled portions 19 and 20, and arranged to co-operate with each other to prevent 35 relative pivotal movement of the slats 10 in one direction materially beyond the surface plane of the extended device, as shown in Fig. 1, and to permit relative pivotal movement of said slats 10 40 in the opposite direction sufficient to enable the device to be rolled up to an inoperative position as shown in Fig. 2. In the preferred form the stops referred to above comprise flanges 21 located at the free edges of the coiled portions 19, 45 and co-operating flanges 22 located at the free edges of the coiled portions 20, as also illustrated in Figs. 1 and 2. In the operative position of the device the flanges 21 project from the associated coiled portions 19 in oblique relation to the median 50 plane of the extended slats 10, while the flanges 22 project from the associated coiled portions 20 in substantial parallel relation to the aforesaid median plane of the extended slats 10. The arrangement is such that when the device occupies 55

its operative extended position, the flanges 21 will project toward the associated flanges 22 and have their free edges located in the angles formed by the flanges 22 so that said flanges 21 and 22 co-operate to prevent relative pivotal movement of the slats 10 in one direction materially beyond the surface plane of said extended device. Furthermore, the flanges 21 and 22 are so constructed and arranged that the free edges of the flanges 22 will move into the angles formed by the flanges 21 when the device is to be rolled up to an inoperative position, the extent of movement of the flanges 22 relatively to the flanges 21 being such as to permit relative pivotal movements of the slats 10 in the opposite direction sufficient to enable the device to be rolled up as set forth above.

In addition to the parts so far described the device preferably includes means whereby the slats 10 are fixed against any relative movement lengthwise of each other, or in other words lengthwise of the coiled portions 19 and 20, without however interfering with the pivotal movements of the slats 10 relatively to each other. In the illustrated example as shown in Fig. 3, the aforesaid means comprises strips 23 of flexible metal secured to the inner surfaces of the slats 10, for instance, by rivets 24, said strips 23 preferably being located along the opposite edges of the device and having an inherent flexibility of such character as to permit the relative pivotal movements of the slats necessary to adjust the device to an extended operative position or to roll up said device to an inoperative position. For the purpose of imparting a finish to the device and also to prevent the entrance of dirt or other foreign matter into the interconnected coiled portions 19 and 20, studs may be provided having heads 25 and shanks 26, the latter being of such dimensions as to fit within the interconnected coiled portions 19 and 20 with the heads 25 designed to close the opposite ends of said interconnected coiled portions 19 and 20, as illustrated in Fig. 4. In the preferred form the shanks 26 are split lengthwise as shown at 27 so as to frictionally fit into the coiled portions 19 and 20 without interference with the relative pivotal movements of the slats 10. In addition the studs are preferably constructed of a metal which is harder than the metal of which the slats 10 are constructed, the shanks 26 in such case being preferably provided with surface projections arranged to bite into the coiled portions for fixing the studs in place; as shown in Figs. 4 and 5 the surface projections may comprise circumferential ribs 28 arranged to wear recesses into the interconnected coiled portions 19 and 20 for the pur-

pose of fixing said studs in their intended position against unintentional removal.

In all of its forms the device presents a highly ornamental appearance and at the same time is capable of being produced in an economical manner and without requiring any particular skill on the part of the operators. In addition the interconnected portions 19 and 20 are of such a type as to provide pivotal connections between adjacent slats 10 which are water-proof and weather-proof so that the device in its operative position assures adequate protection not only against sunlight, but against the elements in all weather conditions. By selecting the proper metal for the construction of the slats 10 the device may be of relatively light weight and at the same time in all of its forms is durable and adapted to resist the effects of the elements for long periods. The interconnected coiled portions 19 and 20 provide pivotal connections which render the device sufficiently flexible to enable it to be rolled up into a compact inoperative position without necessitating any complicated mechanism to effect this result. The device is particularly adapted for use as awnings or canopies to replace the customary fabric awnings or canopies and at the same time may be adapted for other uses as will be apparent.

Various changes in the specific forms shown and described may be made within the scope of the claim without departing from the spirit of the invention.

We claim:

A protecting device of the kind described comprising a plurality of slats arranged in adjacent parallel relation to each other, coiled portions located at opposite edges of said slats, the coiled portions of each slat extending in opposite directions and being interconnected and substantially in surface engagement throughout with the coiled portions of adjacent slats whereby said slats are pivotally connected with each other, and flanges located at the free edges of said coiled portions, one flange of each slat projecting from its associated coiled portion in substantial parallel relation to the median plane of the extended slats and the other flange of each slat projecting from its associated coiled portion in oblique relation to said median plane whereby the flanges of interconnected coiled portions co-operate with each other to prevent relative pivotal movement of the slats in one direction materially beyond the surface plane of the extended device and to permit relative pivotal movement of the slats in the opposite direction sufficient to enable the device to be rolled up to an inoperative position.
